(57) **CLAIM**

The ornamental design for an aviation buffer handle as shown and described.

DESCRIPTION

FIG. 1 is a front isometric view of an aviation buffer handle in accordance with the present invention, illustrating the handle in an environment of use;

FIG. 2 is a first isometric view of the handle illustrated in FIG. 1;

FIG. 3 is a second isometric view of the handle illustrated in FIG. 1;

FIG. 4 is a top plan view of the handle illustrated in FIG. 1;

FIG. 5 is a first side view of the handle illustrated in FIG. 1;

FIG. 6 is a front elevation view of the handle illustrated in FIG. 1;

FIG. 7 is a second side view of the handle illustrated in FIG. 1;

FIG. 8 is a rear elevation view of the handle illustrated in FIG. 1; and,

FIG. 9 is a bottom plan view of the handle illustrated in FIG. 1.

The broken lines in the figures illustrate environmental subject matter only and forms no part of the claimed design.

1 Claim, 3 Drawing Sheets
